UNITED STATES PATENT OFFICE.

GEORGE M. EAMES, OF BRIDGEPORT, CONNECTICUT, AND IRVING F. WEBB, OF ELIZABETH, NEW JERSEY, ASSIGNORS TO THE SINGER MANUFACTURING COMPANY, OF ELIZABETH, NEW JERSEY, A CORPORATION OF NEW JERSEY.

POWER TABLE FOR SEWING MACHINES.

Application filed January 15, 1925, Serial No. 2,540. Renewed January 28, 1928.

This invention relates to improvements in power-tables for sewing and like machines and has for its object to increase the range of adaptability of power-tables to the different requirements of commercial usage.

The present invention is equally applicable to flat and trough top power-tables of either the single or double type, as well as to power-tables comprising a plurality of either single or double aligned sections of either type.

Each power-table section preferably comprises end standards sustaining for vertical adjustment, a table-top supporting end rail, the table-top being provided with driving belt apertures suitably located for the particular variety of driven machine placed thereupon.

Each of the end standards includes a vertically adjustable cross-bar upon which a power-transmitter supporting member is mounted for horizontal adjustment, said member spanning the cross-bars below and longitudinally of the table-top. Clamped upon said supporting member so as to be adjustable lengthwise thereof and angularly thereupon independently of the table-top is an electric-transmitter of any approved type comprising a complete driving unit including an electric-motor, a driving pulley and a treadle-controlled clutch whereby said pulley may be at will operatively coupled with the electric-motor. The transmitter-pulley and the driven machine pulley are connected by a driving belt passing through the table-top belt-apertures.

The present improved power-table therefore provides for vertical adjustment of the table-top without changing the driving belt, because the power-transmitter position may be readily correspondingly adjusted. Table-top substitutions may be readily made for different varieties of machines, as occasion demands in commercial usage, because the transmitter is supported independently of the table-top and its mounting meets the different requirements of adjustment necessary for proper alinement of the driving and driven pulleys with the correspondingly located table-top belt-apertures. Not only may the necessary alinement of the pulleys be readily effected, but thereafter any slack in the belt due to stretching may be taken up by changing the transmitter position by means of the adjustments provided.

The transmitter supporting member is in the form of a tubular bar affording a conduit for the electric current leads and it will be apparent that when the power-table comprises a plurality of aligned sections, said tubular supporting member may serve as a conduit for all of the several current leads, thereby providing a simple solution for all safety requirements. A feature of the present improvement is the facility with which a power-table of the described character may be installed to meet different factory regulations and as previously pointed out the nature of its construction is such as to thereafter more fully meet commercial requirements than was heretofore possible.

In the accompanying drawings, Fig. 1 is a front side elevation of a portion of a trough-type power-table for sewing and like machines, illustrative of the present improvement. Fig. 2 is an end elevation, partly in section of the same. Fig. 3 is a detail sectional view of a portion of the cross-bar of a table-standard, illustrating the transmitter supporting-bar clamping means.

It is to be understood that only so much of a power-table is shown in the drawings as is deemed essential to an understanding of the present invention and it will be obvious that the present improvement is equally adaptable to flat and trough-types of table-tops, as well as to single and double table-sections employed individually or in a plurality of aligned sections, all of which types are common and well known in this art.

Referring to the drawings, a portion of a trough-type, double power-table section is shown as comprising a horizontally disposed table-top portion 1 and a trough 2. It is preferred to support this table-top by only end standards to facilitate setting up of the table and subsequent table-top substitutions. Only the front portion of one of the end standards is shown in the accompanying drawings, the rear leg of said standard having the same construction as the front leg and the other standard or standards being duplicates of that herein disclosed.

The table-top 1 overlies and is removably clamped at each end upon an inverted U-shaped channel-bar 3, which therefore constitutes a transverse supporting rail, there being a similar rail (not shown) at the opposite longitudinal end of said table-top. The

means employed for clamping the table-top upon each supporting rail is shown as comprising an upper clamp-plate 4 disposed transversely of the length of the table-top; 5 bolts as 5 passing through said clamp-plate 4 and the table-top, and spaced lower clamp-plates as 6 bridging the depending members of the rail 3, said bolts being secured by nuts as 7. Suitably riveted upon each rail 3 so 10 as to depend therefrom are two U-shaped channel-bars 8 (only one of which is shown), each constituting a vertically adjustable member of a two-part table-leg. The leg-member 8 is slidably disposed within a similarly shaped leg-member 9, said members being secured in relatively adjusted positions by means of a bolt 10, nut 11 and an elongated slot 12 provided in the leg-member 8.

The leg-members 9 at each end of the table 20 are connected by an inverted U-shaped channel-bar or cross-bar 13, the top wall 14 of which has its ends turned down to form end walls 15. The end walls 15 are each secured by a bolt 16 and a nut 17 upon a leg-member 25 9, which for this purpose is provided with an elongated slot 18 permitting vertical adjustment of the cross-bar 13. Sustained by the cross-bars 13 is an electric-transmitter supporting member in the form of a tubular 30 bar 19 disposed longitudinally of the table, said bar 19 being clamped for horizontal adjustment upon said cross-bars at each end of a table section. The bar clamping means comprises, in each instance, a cap-member 20 and a complementary member 21, which latter rests upon the cross-bar top-wall 14. The rod clamping members are secured upon the cross-bar 13 by bolts as 22 passing through elongated slots 23 in the top-wall 14, said 40 bolts being each secured by a nut 24 bearing against a cross-bar bridging plate 25. This construction evidently provides for horizontal adjustment of the supporting bar 19 upon the cross-bar 13.

45 Mounted upon the supporting bar 19 for adjustment longitudinally of a table-section and angularly about said bar, is an electric-transmitter 26 which may be of any approved type. The electric-transmitter employed in 50 the present instance is constructed substantially in accordance with the disclosure in the U. S. patent to P. A. Herr, No. 1,514,083, Nov. 4, 1924, to which reference may be made for details of construction of the transmitter. 55 In general, the electric-transmitter herein employed, in common with other transmitters of this type, comprises a complete driving unit consisting of an electric-motor 27 of which the shaft (not shown) may be at will 60 coupled with or uncoupled from a driving-pulley 28 by manipulation of a treadle-actuated lever 29. The lever 29 is pivotally mounted upon one of two brackets 30, having supporting flanges as 31 upon which the electric-transmitter feet 32 are secured by bolts 65

as 33. The lower ends of the brackets 30 are each bifurcated to form a depending fork 34 which straddles the supporting bar 19 and is clamped in adjusted position thereupon by means of a set-screw 35 threaded into a plate 36 bridging the fork-branches. The fork-branches are preferably formed to converge toward the base of the opening between them whereby a three-point contact on the bar is obtained by said fork-branches and set-screw 75 35.

The tubular supporting bar 19 affords a conduit for electric-current leads. In the present instance a cable 37, connected with any suitable power source, is conducted 80 through the tubular bar 19 and emerges through an aperture 38 provided in said bar and an aperture 39 provided in an outlet-box 40 suitably clamped upon the bar 19 in an alined position of said apertures 38 and 39. 85 The leads of cable 37 are spliced within the outlet-box to the wires of another cable connected in regulation manner with a switch 41, said switch being connected by a current conducting cable 42 with the motor 27. The 90 switch 41 is in the present instance carried by a casing 43 depending from a lateral arm 44 of one of the clamp-plates 6.

From the foregoing description, it will be apparent that the power-transmitting unit is 95 supported entirely independent of the table-top 1 so that adjustments and substitutions of table-tops may be readily made independently of the transmitter mounting. The complete transmitter may however be adjusted 100 vertically by an adjustment of the position of the cross-bars 13 upon the leg members 9; horizontally in a direction crosswise of the table by shifting the supporting bar clamping means 20, 21 upon the cross-bars 13, and longitudinally of the table by shifting the transmitter brackets 30 longitudinally of the bar 19. In addition the electric-transmitter may 105 be adjusted, as a unit, angularly about the bar 19 by manipulation of the set-screws 35. 110 These unit adjustments of the combined motor and transmitter obviously provide for the shifting of the driving pulley to the different positions it must occupy according to the positions of the belt-apertures of the table-tops employed for different varieties of machines, as well as to take up slack in the driving belt 45 which connects the transmitter-pulley 28 with the driven pulley 46 of the sewing machine 47 sustained by the table-top 115 1. The present construction of power-table therefore fully meets the different commercial requirements in the matter of ready installation; adaptability for different varieties of driven machines, and safety for the operators. 120 125

Having thus set forth the nature of the invention, what we claim herein is:—

1. A power-table for sewing and like machines comprising a table-top, table-top end standards, a tubular supporting member sus- 130

tained by said standards and affording a conduit for electric-current leads, and an electric-transmitter mounted upon said member.

2. A power-table for sewing and like machines comprising a table-top, table-top standards, means for securing the table-top for vertical adjustment upon said standards, a tubular supporting member secured for horizontal adjustment upon said standards ²⁵ affording a conduit for electric current leads, and an electric-transmitter mounted upon said supporting member independently of said table-top.

3. A power-table for sewing and like machines comprising a table-top, table-top end standards, a tubular supporting member sustained by said standards and affording a conduit for electric-current leads, an electric-transmitter, and means for securing said ³⁰ transmitter for adjustment longitudinally of and angularly about said member.

4. A power-table for sewing and like machines comprising a table-top, table-top

standards, a tubular supporting member sustained by said standards and affording a ²⁵ conduit for electric-current leads, an electric-transmitter secured upon said member, an outlet box mounted upon said member at point of emergence of said leads from said member, and an electric-switch sustained by ³⁰ one of said standards for connecting said current leads with said electric-transmitter.

5. A power-table for sewing and like machines comprising a table-top, table-top end standards, a tubular supporting member sustained by said standards affording a conduit for electric current leads, an electric-transmitter, a supporting bracket for said transmitter having a fork straddling said member, and means for clamping the bracket fork ³⁵ ⁴⁰ upon the supporting member.

In testimony whereof, we have signed our names to this specification.

GEORGE M. EAMES.
IRVING F. WEBB.
